UNITED STATES PATENT OFFICE.

JOHN H. DALE, OF NEW YORK, N. Y.

ELECTRIC-LIGHTING FIXTURE.

1,160,859.

Specification of Letters Patent. Patented Nov. 16, 1915.

Application filed April 25, 1914. Serial No. 834,299.

To all whom it may concern:

Be it known that I, JOHN H. DALE, a citizen of the United States, residing at the city of New York, in the borough of Manhattan and State of New York, have invented certain new and useful Improvements in Electric-Lighting Fixtures, of which the following is a full, clear, and exact description.

This invention relates to electric lighting systems and has special reference to that style of lighting fixture which is used in "indirect" lighting systems.

The object of the invention is to provide a fixture of this class which will, to the least extent, obstruct the rays of light which are projected upward toward the ceiling from the lamps that are attached to the fixture.

Another object of the invention is to provide in a simple and compact fixture means for using pull-sockets, and a still further object of the invention is to provide a fixture of this class in which the shade can be readily removed and replaced for cleaning purposes by a simple operation and without disturbing the lamps.

With these and other objects in view, the general construction of my improved fixture comprises the combination of a hollow hub and a shade supporting pan detachably secured thereto, the hub and pan being connected to the center or lowermost point of the shade and being adapted to support the lamps in an upwardly and outwardly inclined position, and to accommodate the pull-chains of the sockets of said lamps by permitting them to pass through the hub and the pan for convenient manipulation at a point below the shade. The hub and pan are supported at the lower end of a tubular stem, which stem is the only part of the fixture interposed between the lamps and the ceiling.

My invention also includes other details and constructions which will be fully herein-after described and particularly pointed out in the claims.

In the accompanying drawings: Figure 1 is a vertical central section of my improved fixture; Fig. 2 is a plan of the hub; and Fig. 3 is a section of the fixture and the lower part of the shade showing how a shade with a different size of opening, from that shown in Fig. 1, can be used in the same fixture.

The fixture comprises two main parts, a hollow hub 1 and a pan 2. These parts may

be either cast, or formed of sheet metal; as shown they are rather heavy castings. The hub is somewhat of a diamond shape in vertical section, the upper half having a central boss 3 internally screw-threaded so as to screw on to the lower end of a tubular stem 4 extending from the ceiling and which forms the sole support for the fixture. The lower half of the hub 1 is also provided with a central boss or neck 5 of larger size than the boss 3 and having an internal screw-thread. The pan 2 is provided with a central upwardly extending neck 6 having an external screw-thread adapted to engage with the thread in the boss 5. A passage 7 leads through the neck 6 and affords free communication to the interior of the hub 1. The upwardly extending sides 8 of the pan 2 approach the wall of the hub 1, but are separated therefrom a sufficient distance to admit the shade therebetween.

The shade 9 is of the usual inverted type commonly used in the indirect lighting systems; it may be either opaque having a reflecting inner surface or it may be translucent, making the fixture "semi-indirect." In any case the central or lowest point of the shade is provided with an opening which may or may not be surrounded by a flange or neck 10. Shades of this character are usually provided with such a flange for which reason it is shown in the drawing. These openings or flanges are of different stock sizes and my fixture is designed to receive and support shades which have any of the usual sizes of openings at the center. The shade is adjusted to the fixture by first unscrewing the pan 2 from the hub 1 and then placing the shade in the position shown in Figs. 1 or 3 so that its inner surface will rest against the under wall of the hub and substantially concentric therewith. The pan is then screwed into the hub until its bottom or side flange 8 comes in contact with the exterior of the shade. The external diameter of the boss 5 is such that the shade having the smallest opening will neatly fit around it while the internal diameter of the side flange 8 of the pan is such that the flange 10 of a shade having the large size of opening will neatly fit into it. When a shade having openings of either of these two sizes is used, it will be maintained firmly in a concentric position either by the boss 5 or the flange 8, depending upon which size of opening is used. When a shade having an open-

ing of an intermediate size is to be adjusted to the fixture, such, for instance, as shown in Fig. 1, I use a spacing ring or collar 11 which rests freely in the pan 2 and which 5 fills the space between the external surface of the boss 5 and the internal surface of the flange 10 and thereby centers and maintains the position of the shade.

Fig. 3 shows a shade having the smallest 10 size of opening and, as described, is centered by direct contact with the boss 5. It will be seen that when the shade is attached to the fixture in the manner described it is held firmly between the pan and the hub in 15 a perfectly concentric position; it is held in place without screws and the only part of the fixture necessary to remove in order to remove the shade for cleaning purposes, is the pan 2 which can be readily and 20 quickly unscrewed. This method of supporting the shade I believe to be novel in indirect lighting systems where the usual practice is to attach the upper edge of the shade either to a spider extending from 25 the central stem or by means of chains or rods leading upward from the outer edge of the shade. All such contrivances are objectionable because they obscure the light from the lamps which are inclosed within 30 the shade.

The lamps 12, any suitable number of which may be used, are supported directly by the hub 1 from the upper wall of which they radiate in an outwardly and upwardly 35 inclined position. Being thus disposed no part of the fixture except the central stem 4 is located between the lamps and the ceiling, not even the sockets 13 of the lamps themselves are above the lamps, the result of 40 which is that the full benefit of the candle-power of the lamps is obtained for illuminating purposes and shadows and "spots" are avoided. The lamp sockets are sustained by means of the usual threaded nipples 14 45 fixed in the upper wall of the hub 1 and adjacent to each nipple a perforation 15 through the wall of the hub is provided through which to pass the chains 16, when pull-sockets are used, for controlling the respective lamps. These chains after passing 50 through the perforations 15, lead through the interior of the hub 1 and the passage 7 in the pan to a suitable point below the fixture in a convenient position to be reached and manipulated. All of the chains thus 55 lead through one central opening and become less conspicuous than if they were widely separated or extended over the upper edge of the shade, as is often done.

60 The hollow hub 1 also has the additional function of housing the wiring of the fixture. The two main wires 17 and 18 lead

downward through the hollow stem 4 and are spliced to branch wires 19 and 20, one pair leading to each of the lamps and passing thereto through the nipples 14. This wiring is shown conventionally in Fig. 1 but in practice it will be understood that the wires being heavily insulated and having taped joints, will occupy considerable 65 of the space within the hub. They can, however, be so packed into the hub as to leave sufficient space for the pull-chains to pass through.

While I have referred herein to the part 1 75 specifically as the hub and the part 2 as a pan attached thereto, it is to be understood that this hub and pan when taken together constitute a single hub or hub-like structure, which engages with the central point of an 80 upwardly extending shade and from which the lamps radiate upwardly and outwardly and that this hub constitutes a housing for the wires and affords a passage for the chains leading from the sockets inside of 85 the shade to the exterior thereof.

What I claim is:

1. An indirect electric lighting fixture comprising a shade, a hub detachably connected therewith at its central portion, 90 lamps supported by said hub, said hub being provided with a central passage and pull-chains for controlling said lamps and leading through said passage.

2. An indirect electric lighting system 95 comprising a two-part hub, the members of which are detachably secured together, one of said parts being adapted to support a shade and the other part being hollow and supporting lamps, the wiring of said lamps 100 being housed within the said hollow part, said hub being provided with openings and pull chains leading through said openings.

3. An indirect electric lighting fixture 105 comprising a hub having a passage therethrough; a plurality of pull-sockets attached to said hub, pull-chains extending from said sockets through the passage of said hub and a shade mounted upon said hub.

4. In an electric light fixture the combination of a shade having a central opening; a pan adapted to support said shade, said pan having a central neck and a peripheral flange, and a spacing ring inserted between 115 the edge of the opening in the shade and the central neck of the pan for the purpose set forth.

In witness whereof I subscribe my signature, in the presence of two witnesses.

JOHN H. DALE.
